CASING FOR POPCORN VENDOR

James J. Hill, Miami, Fla., assignor to Apco, Inc., a company of New York

Application February 19, 1957, Serial No. 44,922

Term of patent 14 years

(Cl. D52—3)

The single figure of the drawing is a front perspective view of a casing for popcorn vendor, showing my new design.

The undisclosed side of the popcorn vendor is substantially the same in appearance as the side shown in the drawing.

The dominant features of the design are shown in full lines.

I claim:

The ornamental design for a casing for popcorn vendor, as shown and described.
